United States Patent Office.

J. H. PATTEE, OF MONMOUTH, ILLINOIS.

Letters Patent No. 97,311, dated November 30, 1869; antedated November 20, 1869.

IMPROVEMENT IN VAPOR-BURNERS.

The Schedule referred to in these Letters Patent and making part of the same

To all whom it may concern:

Be it known that I, J. H. PATTEE, of the city of Monmouth, county of Warren, and State of Illinois, have invented certain new and useful Improvements in Vapor-Burners; and I do hereby declare that the following is a full, clear, and exact description of the same, reference being had to the accompanying drawings, making a portion of this specification, in which—

Figure 1 is a vertical central sectional view of my invention.

Figure 2 is a cross-section, on the line $x x$, fig. 1.

Similar letters of reference indicate corresponding parts in both figures.

The nature of this invention relates to improvements in vapor-burners; and

The invention consists in the arrangement by which the gasoline or other light oil to be vaporized, is made to surround the cylinder which feeds the burner in a manner to insure regular heat for vaporizing, and no leaking of jets of vapor to create unpleasant odors, unsightly lights, and unpleasant, hissing noise.

It also consists in the simple and effectual device for regulating the quantity of air to be mixed with the hydrocarbon-vapor.

It further consists in the spherical shape of the burner proper for reflector-purposes, and in the arrangement of the same on the feed-pipe, in a manner to prevent any irregular or spouting action of the vapor affecting the jets from the burners.

To enable others to understand the construction and operation of my invention, I will proceed to describe it with reference to the drawings.

Letter A represents the vaporizing-chamber, connected with the pipe B, leading from the reservoir containing the oil, in the usual manner.

This chamber A entirely surrounds the pipe C, leading to the burner proper, or it may only partly surround it.

D is a pipe, leading downward from the chamber A, and into the pipe Y.

E is a screw-bolt, with a point at the upper end, tapered, and fitting neatly into a small opening in the upper end of the pipe Y, for regulating the flow of vapor.

H represents a short, hollow pipe, screwed into the lower end of the pipe C, and provided with a flanged head at the lower end, by means of which it may be turned and the distance adjusted between the flanged head and the top of the pipe Y.

J represents a hollow globe, supported on the pipe C, by being attached at the lower edge.

L is a flange extending around the globe J.

S S S represent the small holes through which the burning vapor issues. These holes are arranged below the flange L, which gives the burning jets, with the incline of the globe where they issue, a direction shown by the red line Z, adding much thereby to the appearance and the effect of the light.

The advantages of this burner are—

First, the vaporizing-chamber surrounding the pipe C, as it does, the heat from the pipe C passes to the oil in the centre of the chamber, and around the outside of the oil by the chamber itself, thereby insuring certainty in vaporizing even at a low temperature.

Second, the device for admitting air places the control of the amount of the same under the will of the operator.

Third, the pipe C, passing as it does, to near the top of the globe J, prevents the vapor from passing directly to the jets, and the globe serves as a reservoir to hold the vapor and produce a regular pressure on the jets, thereby preventing the spouting, irregular burning usual with such lamps.

The lower half of the globe, being polished, will serve as a reflector, and increase the brilliancy of the light.

F is the usual reservoir for starting the light.

Having thus described my invention,

What I claim as new, and desire to secure by Letters Patent, is—

1. The combination of the vaporizing-chamber A with the pipe C, when the chamber A surrounds the pipe C, in a manner to bring the oil from the reservoir in direct contact with the pipe C, as and for the purpose set forth.

2. The hollow pipe H, combined with and operating between the pipes C and Y, for the purpose of regulating the admission of the air into the pipe C, as and for the purpose set forth.

3. The globe J, with flange L and jets S S S, combined with the pipe C, substantially as described and for the purpose set forth.

Signed at Galesburg, Illinois, this 15th day of March, 1869.

J. H. PATTEE.
